(57) **CLAIM**

I claim the ornamental design for a cable holder, as shown and described.

DESCRIPTION

FIG. 1 is a perspective view of a cable holder showing the new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a perspective view in a disassembled state thereof; and,

FIG. 9 is a perspective view in a state of use thereof. Broken lines illustrate environmental condition only and form no part of the claimed design.

1 Claim, 9 Drawing Sheets
